UNITED STATES PATENT OFFICE

2,575,618

FLUSH TYPE FILL BOX

John D. Dillard, Little Rock, Ark.

Application April 11, 1947, Serial No. 740,940

1 Claim. (Cl. 220—57)

1

The present invention relates to fill boxes and its consists in the combinations, constructions and arrangements of parts herein described and claimed.

Generally, the invention comprises a fill box of the type adapted to lie flush with the surface of the ground and provided with a housing, an outer cover having a grooved portion with a gasket mounted therein and adapted to receive an upwardly extending annular portion of the housing and an inner cover adapted to be quickly and easily removable and provided with a locking means. A sand trap is provided adjacent the outer cover and a water trap is provided adjacent the inner cover which is removably mounted upon a replaceable nipple.

It is an object of the invention to provide a fill box having a plurality of traps for sand, water and the like.

Another object of the invention is the provision in a device of the character set forth, of threadless covers.

Another object of the invention is the provision of novel means for locking the inner cover of a mechanism as above set forth.

Another object of the invention is the provision of a novel seat construction for the inner cover of a fill box.

Other and further objects of the invention will become apparent from a reading of the following specification taken in conjunction with the drawings, in which:

Figure 1 is a plan view of an embodiment of the invention.

Figure 2 is an enlarged plan view of the device shown in Figure 1, with certain parts removed.

Figure 3 is an enlarged sectional view, taken along line 3—3 of Figure 1.

Figure 4 is a bottom plan view of a cover forming a part of the invention.

Figure 5 is an enlarged sectional view taken along line 5—5 of Figures 2 and 3.

Figure 6 is an enlarged sectional view taken along line 6—6 of Figure 2.

Figure 7 is an enlarged sectional view taken along line 7—7 of Figure 4.

Figure 8 is a sectional view taken along line 8—8 of Figure 2, and

Figure 9 is a sectional view taken along line 9—9 of Figure 4.

Referring more particularly to the drawings, there is shown therein a fill box comprising a housing of generally circular cross-section having an interiorly threaded dependent portion 10 for the reception of a conventional fill pipe (not shown), an enlarged central section 11 and a further enlarged top section 12.

Spaced from the wall of the top section is an integrally formed upwardly extending continuation 13 of the wall of the central section 11, the top of which is adapted to be received in an annular groove 14 formed in the underside of a top cover 15. Within the groove 14 is provided a gasket 16.

The cover 15 is adapted to lie flush with the upper extremity 17 of the top portion 12 of the housing and is provided with a centrally located slot 18 having a cross piece 19 extending thereacross.

The continuation 13 is provided with a pair of inwardly extending locking lugs 20 and the cover 15 has attached to its underside, by means of screws 21, a pair of locking plates 22 which are angularly disposed, as best shown in Figure 7.

The continuation 13 and the wall of the top portion 12 of the housing form therebetween a sand trap 23.

A nipple 24 is exteriorly threaded at its bottom portion and is adapted to be removably engaged in the dependent portion 10 of the housing and extend upwardly therefrom. It is provided with a tapered upper edge 25 upon which an inner cover 26 having a dependent flange 27 is adapted to be removably mounted. The flange is provided with a gasket 28 upon its interior face.

To the upper side of the inner cover is pivotally mounted, by means of a pin 29, a locking bar 30 having integrally formed wedge-shaped outer faces 31 and an integrally formed abutment 32 upon each face. The faces 31 are adapted to pass beneath locking dogs 33 formed on the inner surface of the central section 11 of the housing.

Adjacent the outer end of one of the faces 31, there is provided a pair of upwardly extending brackets 34 each having an opening 35 extending laterally therethrough. The brackets are interconnected at their inner ends with a pin 36 and a lock bolt 37 having an opening 38 is hingedly mounted thereon and adapted to extend when in its outward position to a point adjacent the outer end of the face 31. The lock bolt 37 is provided with an integrally formed fingerpiece 39. The openings 35 and 38 are adapted to register with one another when the bolt 37 is in its outward position.

An additional sand and water trap 40 is provided in the space between the outer side of the nipple 24 and the inner side of the wall of the central portion 11 of the housing.

In operation, it will be apparent that, after the fill box is used, the inner cover 26 is first placed in position upon the nipple 24 and that the gasket 28 will form a sealed joint with the

tapered portion 25 of the nipple when the locking bar 30 is turned so that the faces 31 thereof come into engagement with the dogs 33 forcing the cover downwardly. The lock bolt 37 may then be swung to its outward position and one dog 33 will be held between it and the abutment 32 on that side of the locking bar, thus preventing rotation in either direction. A padlock may then be passed through the openings 35 and 38, thus preventing unauthorized removal of the cover 26.

The outer cover 15 may now be placed in position and turned by a suitable tool being placed in the slot 18 under the cross-piece 19, thus causing the locking plates 22 to bear against the locking lugs 20 and compressing the gasket 16 between the cover and the continuation 13.

It will be seen that two compartments or traps 23 and 38 are provided by this structure. It will also be apparent that the nipple 24 may be easily and quickly replaced whenever necessary.

While but one form of the invention has been shown and described herein, it will be readily apparent to those skilled in the art that many minor modifications may be made without departing from the spirit of the invention or the scope of the appended claim.

What is claimed is:

In combination with a circular housing having a nipple projecting upwardly therein, a cover for said nipple, dogs projecting inwardly from the walls of the housing, a horizontally extend-

ing bar centrally pivoted upon the top of said cap and having end portions extending beyond the edge of said cap and having transversely inclined upper faces constituting cam surfaces engaging under the dogs to force the cap downwardly upon said nipple, an integrally formed abutment extending upwardly from each of said cam surfaces at one side thereof, an arm pivoted for radial vertical swinging movement mounted upon one end portion of said bar in circumferentially spaced relation to the abutment on said last named end portion and contiguous in its outward position with one side of one of said dogs when an abutment is contiguous with the other side.

JOHN D. DILLARD.
